His Attorney.

UNITED STATES PATENT OFFICE

BRUNO HOFFMANN, OF SPANDAU-WEST, GERMANY, ASSIGNOR TO GENERAL ELECTRIC COMPANY, A CORPORATION OF NEW YORK

CENTRIFUGAL COMPRESSOR

Application filed June 25, 1929, Serial No. 373,673, and in Germany July 16, 1928.

It is well known in the operation of centrifugal compressors that the efficiency of the compressor drops off rapidly for very low outputs of the compressor, and that there is 5 soon reached a point on the output-efficiency curve where the efficiency becomes approximately zero and the compressor ceases to pump. This point is ordinarily known to those skilled in the art as the pumping limit 10 of the compressor. This pumping limit of the compressor is determined by various of its characteristics among which are the speed at which the compressor is driven and the effective cross-section of the suction impellers 15 which is ordinarily determined by their diameters.

It is an object of this invention to increase the pumping range of a centrifugal compressor by decreasing its pumping limit. This decrease in the pumping limit may be effected by decreasing the diameters of the successive impellers toward the high pressure end, and by providing an arrangement to by-pass any 20 desired number of the low pressure impellers, and thereby decrease the effective cross-section 25 of the suction of the compressor.

For a more complete understanding of my invention and its operation reference may be had to the following description taken in connection with the single figure of the accompanying drawing which represents diagrammatically a centrifugal compressor constructed according to my invention provided with connections for by-passing any desired number 35 of the low pressure impellers.

Referring to the drawing, a rotary compressor with impellers decreasing in diameter toward the high pressure side is shown at 1. The compressor is provided with a suction pipe 2 and a discharge pipe 4. If desired, the compressor may be provided with interstage coolers 5 and 6 through which the compressed medium passes in its travel through the compressor. The pipes for conveying cooling fluid to and from the coolers are indicated at 10 and 11, respectively. Connecting the suction pipe 2 with the intake 7 of the first cooler is a conduit 8 provided with a valve 9. Located in the suction pipe 2 between the compressor and the junction of the conduit 8

with this suction pipe is a throttle valve 3, which is illustrated as a flap valve though obviously any other valve means might be used if desired. In case it is not found advisable to use the interstage coolers 5 and 6 they 55 may be omitted and the conduit 8 connected to the intermediate impeller to which the pipe 7 is illustrated as connected.

In the normal operation of my compressor the throttle valve 3 is open and the valve 9 60 is closed and the compressed medium passes completely through the compressor in the ordinary manner. When the quantity of the compressing medium required of the compressor falls below its pumping limit the valve 9 65 is opened and the throttle valve 3 closed, whereupon a predetermined number of the low pressure impellers are by-passed so that the first effective impeller is an intermediate one of smaller diameter than the first impeller, that is of smaller effective cross-section. The resulting decrease in pressure due to the by-passing of a number of the impellers may be compensated for by increasing 70 the speed of the compressor. 75

The particular arrangement which I have above outlined has the decided advantage that the low pressure impellers are working in a partial vacuum so as to create a minimum of frictional resistance and cause a 80 minimum of energy loss. In addition, if by any chance any air should leak past the throttle valve 3 it will be drawn through the pipe 7 into the intercooler 5, and so prevent any accidental excessive heating in the 85 low pressure stages.

In accordance with the patent statutes, I have described what I consider as the preferred embodiment of my invention, but I do not desire to be limited thereto but intend 90 in the appended claims to cover all modifications within the spirit and scope of this invention.

What I claim as new and desire to secure by Letters Patent of the United States is: 95

1. In combination, a multiple impeller centrifugal compressor in which the diameters of the impellers decrease toward the high pressure end, and means for decreasing the pumping limit of the compressor 100.

comprising means for by-passing an impeller at the low pressure end of the machine whereby the effective suction cross-section of the compressor is decreased.

5 2. In combination, a multiple impeller centrifugal compressor in which the diameters of the impellers decrease toward the high pressure end, and means for decreasing the pumping limit of the compressor
10 comprising means for connecting an intermediate impeller to the suction of the compressor.

3. In combination, a multiple impeller centrifugal compressor in which the diameters of the impellers decrease toward the high pressure end, and means for decreasing the pumping limit of the compressor comprising a valve for closing the main suction of the compressor, and a conduit with a valve therein adapted to simultaneously connect the suction with an intermediate impeller.

4. In combination, a multiple impeller centrifugal compressor in which the diameters of the impellers decrease toward the high pressure end, an intermediate cooler interposed in the path of the air through the compressor, and means for connecting the suction of the compressor to an intermediate impeller in front of said cooler for decreasing the pumping limit of the compressor.

In witness whereof, I have hereunto set my hand, this 11th day of June, 1929.

BRUNO HOFFMANN.
